UNITED STATES PATENT OFFICE

124,998

DESIGN FOR A LIGHTING FIXTURE

Edwin F. Guth, St. Louis, Mo.

Application October 30, 1940, Serial No. 96,183

Term of patent 14 years

To all whom it may concern:

Be it known that I, Edwin F. Guth, a citizen of the United States and a resident of St. Louis, Missouri, have invented a new, original, and ornamental Design for a Lighting Fixture, of which the following is a specification, reference being had to the accompanying drawings, forming part thereof, in which

Fig. 1 is a perspective view of the lighting fixture, observed from beneath, showing my new design;

Fig. 2 is an end elevational view of the same;

Fig. 3 is a top plan view thereof;
Fig. 4 is a side elevational view thereof; and,
Fig. 5 is a bottom plan view thereof having one corner broken away for convenience of illustration.

For convenience Figs. 1 and 2 are shown on a reduced scale.

I claim:

The ornamental design for a lighting fixture, substantially as shown and described.

EDWIN F. GUTH.
